ROTARY PUMP FOR LIQUEFIED GASES

Roger V. Carlson, Kenmore, N. Y., assignor to
The Linde Air Products Company, a corpora-
tion of Ohio

Application January 9, 1947, Serial No. 721,134

8 Claims. (Cl. 103—96)

1

This invention relates to rotary pumps for liquefied gases, particularly multi-stage rotary pumps for pumping liquefied gases having normal boiling points substantially below 233° K., such as liquid nitrogen, and capable of delivering adequate quantities of such low temperature liquid at a considerably elevated pressure.

The pumping of liquefied gases having low boiling points involves unusual problems due to the great volatility of the liquid and its extremely low temperature. The temperature change from room temperature to that of the liquefied gas causes severe contraction of the pump parts and the construction must allow for such contraction without incurring increased friction or affecting the pumping efficiency. The volatility of the liquid, which is increased by natural heat flow toward the liquid from the surroundings, makes pumping of such a liquid quite difficult as generation of heat by the operation of the pump adds to the difficulty and may cause gas binding and failure of operation. The low temperature also makes it impossible to employ ordinary lubricants and therefore bearings of the customary type cannot be used.

To obtain higher delivery pressures when pumping a liquefied gas by rotary pumps it is found necessary to employ two or more stages and when several stages are provided in a single casing with a single drive shaft the difficulties of accommodating the contraction of the parts have previously resulted in the employment of complicated constructions. Multiple staging introduces the problem of interstage sealing, which is necessary because the increased energy of the liquid in the higher pressure stage causes vaporization if it leaks toward a lower pressure stage. Such interstage sealing must be accomplished without incurring excessive friction and also be unaffected by expansion and contraction of the parts. It has also been proposed to use bearings made of bonded carbon or graphite in pumps for low temperature liquefied gas, particularly liquid oxygen. Such material is self-lubricating and is not affected by the low temperature. It does have the disadvantage, however, that it tends to wear rapidly under the high radial bearing loads which occur in turbine-type rotary pumps operating at high discharge pressures. Thus solutions that may suggest themselves for many of the difficulties are conflicting in that they may enhance others.

The principal object of the present invention is therefore to provide a pump for liquefied gases such as liquid nitrogen or liquid oxygen embody-

2

ing an improved combination of features and association of parts that successfully overcomes the difficulties set forth above. The improved pump of the present invention results in part from the discovery that ball bearings are operable successfully in contact with clean liquefied gases of the low boiling point type without requiring fluid or semi-solid lubricants.

Other objects of the invention are to provide 10 a multi-stage pump in which two adjacent impellers may be fixed to a common drive shaft without incurring difficulties caused by expansion and contraction of the parts by employing a shaft bearing that axially positions the shaft with respect to the casing at a point between the impellers; and to greatly simplify the construction 15 of a multi-stage pump for liquefied gas by employing an inboard shaft bearing arrangement between two stages that functions to position the 20 shaft and rotary impellers axially as well as radially with respect to the casing and also functions as an interstage seal.

It is also an object of the present invention to provide a multi-stage pump for liquefied gases 25 with a novel relationship of the impellers to produce substantially greater discharge capacity and increased discharge pressure.

Other objects and features of novelty will be 30 apparent from the following description and the accompanying drawings in which:

Fig. 1 is a view of a longitudinal cross-section through a pump embodying the principles of the present invention, the extended drive shaft portion of the pump being broken away; and

Fig. 2 is an enlarged fragmentary sectional view showing the mounting of the ball bearing in the pump.

Referring now to the drawing, the pump illustrated is of the two-stage type and has a main 40 frame or casing 10 containing first and second stage annular pumping channels 11 and 12 with a partition 13 between them. Operating in the pumping channels 11 and 12 are rotary impellers 14 and 15 respectively provided with suitable 45 blades 16 at their peripheral portions for propelling the fluid through the pumping channels. Each pumping channel is provided with a suitable inlet and outlet passage, which passages do not appear in the section as shown. The outlet 50 of the first stage channel 11 is connected to the inlet of the second stage channel 12. The arrangement of the pumping channels and their inlet and outlet passages is similar to that shown and described in United States Patent No. 2,340,-

55 787. Such arrangement is not illustrated since it

forms no part of the present invention. According to the present invention, however, the second stage pumping channel 12 and impeller 15 are made substantially wider than the first stage channel 11 and its impeller. One side of the casing 10 is closed by a cover 11 which is shaped internally to form part of the pumping channel 12 and to provide close clearance between it and one side of the impeller 15 and is also formed with a cup-like central depression 18 for enclosing the hub 19 of the impeller 15. The other side of the casing 10 is provided with a closure 20 similar to the cover 11 but having an annular central member 21 secured thereto. The central member 21 provides a closure for the hub portion 22 of the impeller 14 and also has secured gas-tightly thereto a tubular extension 23 for enclosing an extended drive shaft 24. The member 21 also has a portion extending inward toward the shaft 24 on the left side of the hub 22 to form a fluid barrier 21' to impede circulation of liquid into extension 23.

The drive shaft 24 extends axially into the casing 10 and the impellers 14 and 15 are rigidly secured thereon. To this end the drive shaft 24 has an integral collar 25 adjacent the inner side of the impeller 14, the hub portion 22 of which extends outwardly and is internally threaded to engage threads 26 formed on the shaft 24. The impeller 14 is thus threaded on the shaft 24 to abut tightly against the collar 25. To the right of the collar 25 the shaft has a cylindrical portion 27 adapted to carry the inner race 28 of a bearing assembly indicated generally at 29. The bearing 29 is of the type having rolling elements between annular races, preferably a ball bearing. The inner side of the impeller 15 is provided with an annular portion 30 that clamps the race 28 against the collar 25. The rightwardly extending hub portion 19 of the impeller 15 is internally threaded to engage threads 31 formed on the inner end of the shaft 24. If desired, the end of the shaft may be formed with flat areas as at 31' to provide a means for gripping it with a wrench so that the impeller 15 may be secured tightly.

The ball bearing 29 is preferably of the type which is self-centering so as to position the shaft axially as well as radially. The bearing may have one or more rows of balls or it may employ rollers. It is also preferable that the balls or rollers be held out of contact with each other. As shown in the drawing, the bearing is provided with a single row of balls 32 between the inner race 28 and an outer race 33 and spaced from each other by a suitable retainer 34. The outer race 33 is rigidly secured with respect to the partition 13 by retaining rings 35 and 36. To this end the partition 13 has an opening therethrough with a shoulder 37 and an enlarged threaded portion 38. The rim of the ring 35 has threads engaging the threads of opening 38 and abuts tightly against the shoulder 37. The ring 35 has a bore 39 into which the outer race 33 is fitted so as to abut against the bottom of the bore 39 which is formed by an annular flange or shroud portion 40 of the ring 35. The shroud portion 40 extends radially inwardly for a distance sufficient to completely cover the space between the inner and outer races. The outer race is clamped in place by the ring 36 which has external threads engaging those of the bore 38 and has at its inner rim a shroud 41 which covers the space between races 28 and 33. The shrouds 40 and 41 form a labyrinth type of in-

terstage fluid seal to prevent flow of liquid from the high pressure stage through the ball bearing and into the low pressure stage.

The shaft 24 passes through a stuffing box 5 at the outer end of the housing 23, which stuffing box may be of the customary type or for example as shown in United States Patent No. 2,296,640. A supporting bearing is also provided at the outer end of the shaft 24 which may be of any customary type but constructed so that it allows for axial expansion and contraction movement of the outer end of the shaft.

From the above description it will be seen that a great simplification of construction has been effected in a rotary multi-stage pump for low temperature liquefied gases. Previously it had been necessary to provide axially adjustable connections between the drive shaft and the impellers, to provide thrust bearing means for centering each impeller in its pumping channel, to provide means such as balance cylinders for counteracting the resultant radial force of the liquid pressure acting on the high pressure stage impeller, and to provide means for reducing the axial pressures acting on the impeller hub. According to the invention such complications are avoided by utilizing a rolling element type of bearing positioned in the partition between the impellers, the bearing being constructed to withstand substantial radial loads and also to resist substantial axial forces. A two-point contact ball bearing 29 is found to give good results in resisting the combined radial and axial forces because the rotating speeds of the pumps are in excess of 1,500 R. P. M. For heavier duty a double-row ball bearing may be substituted for the single-row type.

The location of the bearing 29 in the partition 13 between the impellers 14 and 15 allows the impellers to be rigidly fixed to the shaft 24 so that the bearing maintains both impellers centered in their pumping channels. The axial movements of the parts due to expansion and contraction are thus symmetrical and the same 45 in amount for each impeller. Since the casing 10 is of cast metal and the shaft is made of wrought metal, their coefficients of expansion are different, but the distance between the center of the bearing and the furthest side of each impeller is so short that the effect of differential 50 expansion and contraction is now small enough to be negligible and the clearances between the covers 20 and 11 and the sides of impellers 14 and 15 remain at the desired close values for efficient operation.

As previously mentioned the invention relies in part upon the discovery that metal bearings of the rolling element type are successfully operable without customary lubricants when subject to 60 low temperature liquefied gases. It has been universal practice to run ball bearings in an oily or grease lubricant even though there is very little if any sliding friction. The lubricant preserves the fine finished surfaces of the balls and 65 races and removes heat due to the metal resilience at the rolling contact points. In the pump according to the invention no oily lubricant can be used and although the liquefied gas such as liquid nitrogen does not appear to provide any 70 lubricating qualities for sliding friction, it is inert with respect to the metal of the bearing and it effectively removes the rolling contact heat. It is also desirable that the rolling elements shall not contact directly with each other to avoid high 75 velocity sliding friction between adjacent ele-

ments. Thus it is preferable to employ a suitable ring-shaped retainer provided with spaced pockets for the balls. The retainer travels with the balls and any friction that may occur between the retainer and the balls is relatively small.

The metal of which the bearing is made should be chosen according to the character of the liquefied gas being pumped. With non-oxidizing gases such as liquid nitrogen the bearing balls and races may be made of the customary carbon or low alloy tool steels provided that care is taken to prevent rusting before the pump is put into service. In a pump for liquid oxygen, rusting during idle periods may be difficult to prevent and it will be preferable to use bearings made of the hard stainless metals such as stainless steels. Certain hard surface corrosion-resistant surface treatments may also be used.

For efficient operation, excessive leakage from the high pressure stage toward the low pressure stage should be prevented. To this end the bearing is constructed to prevent or limit such leakage. With a ball bearing, adequate sealing is accomplished by the shroud flanges 40 and 41 that cover the space between the races 28 and 33 that are arranged to have a very close running clearance with the sides of the inner race 28. The clearance between the side of the impeller 15 and the ring 36 is also kept small so that in effect a labyrinth type of seal is provided. Such sealing arrangement is found to be adequate as a small amount of leakage can be tolerated without a measurable effect on the pumping. Such small amount of leakage is advantageous to bring liquefied gas into contact with the rolling elements which are thereby adequately cooled by a clean liquid.

In rotary liquid pumps of the type disclosed herein it has been customary to make the second stage impeller of the same width or narrower than the first stage impeller on the theory that the liquid is slightly compressed due to the increased pressure. It has been discovered, however, that with liquefied gases of the character of liquid nitrogen, both increased discharge capacity and higher discharge pressure are attainable if the bladed portion of the second stage impeller is made wider than the first stage; with of course a corresponding greater width of the pumping channel in which the bladed portion runs. For example, when the second stage impeller of a two-stage pump was made almost twice the width of the first stage, the discharge capacity increased from 175,000 cubic feet per hour with the narrow second stage impeller to 240,000 cubic feet per hour with the wider impeller when discharging against a pressure of 225 p. s. i. gauge. For a given discharge rate, the pump with the wider second stage impeller easily attained a considerably higher discharge pressure. It is not essential that the second stage be exactly twice as wide as the first stage because any substantial increased width provides improved discharge capacity and/or pressure, although increased widths beyond two times are not expected to provide sufficient further improvement worth the increased weight of the parts.

Although a preferred embodiment of the invention has been described in detail it will be understood that modifications in details of construction may be made and certain features used without others without departing from the spirit and scope of the invention as defined in the claims.

What is claimed is:

1. A multi-stage rotary pump having a casing, at least two rotary impellers therein, an annular pumping channel for the peripheral portion of each of said impellers, and an axially extending drive shaft for said impellers, said casing having a partition between the pumping channels, said impellers being secured to the shaft on opposite sides of said partition, and a bearing for said shaft disposed between the impellers, said bearing being of the type having rolling elements between annular inner and outer races and including interstage fluid sealing means, the inner race being secured to the shaft and the outer race being supported in said partition, said bearing and seal being constructed and arranged to position said shaft and rotors radially and axially with respect to said partition.

2. A multi-stage rotary pump having a casing, at least two rotary impellers therein, an annular pumping channel for the peripheral portion of each of said impellers, and an axially extending drive shaft for said impellers, said casing having a partition between the pumping channels, said impellers being secured to the shaft on opposite sides of said partition, and a bearing for said shaft disposed between the impellers, said bearing being of the type having balls engaged between annular inner and outer races and including interstage fluid sealing means, the inner race being secured to the shaft and the outer race being supported in said partition, said bearing and seal being constructed and arranged to position said shaft and rotors radially and axially with respect to said partition.

3. A multi-stage rotary pump having a casing, at least two rotary impellers therein, an annular pumping channel for the peripheral portion of each of said impellers, and an axially extending drive shaft for said impellers, said casing having a partition between pumping channels, said impellers being secured to said shaft on opposite sides of said partition, and a ball type bearing for said shaft disposed between the impellers, said bearing having its inner race secured to the shaft and its outer race mounted in means securing it to said partition, said securing means including shrouding flanges providing a fluid seal, said bearing and seal being constructed and arranged to position said shaft and rotors radially and axially with respect to said partition.

4. A multi-stage rotary pump having a casing with at least two pumping channels each having inlet and outlet channels, rotary impellers having bladed peripheral portions operating in each of said pumping channels and an axial drive shaft for said impellers, one of said impellers and its pumping channel constituting a later stage being substantially wider than the prior stage.

5. A multi-stage rotary pump having a casing with at least two pumping channels each having inlet and outlet channels, rotary impellers having bladed peripheral portions operating in each of said pumping channels and an axial drive shaft for said impellers, one of said impellers and its pumping channel constituting a later stage being substantially wider than the prior stage, said casing having a partition between the pumping channels, said impellers being secured to said shaft on opposite sides of said partition, and a bearing for said shaft between the impellers and mounted in said partition, said bearing including interstage fluid sealing means and being constructed and arranged to position said shaft and

rotors radially and axially with respect to said partition.

6. A multi-stage rotary pump according to claim 5 in which said bearing is of the type having rolling elements between inner and outer annular races.

7. A multi-stage rotary pump comprising a casing with first and second stage pumping channels, first and second stage rotary impellers having bladed peripheral portions operating in said respective channels and an axial drive shaft for said impellers, the second stage channel and at least the peripheral portion of its impeller being substantially wider than the first stage channel and impeller thereby providing improved capacity and/or pressure characteristics when pumping liquefied gas.

8. A multi-stage rotary pump comprising a casing with first and second stage pumping channels, first and second stage rotary impellers having bladed peripheral portions operating in said re-

10 spective channels and an axial drive shaft for said impellers, the second stage channel and at least the peripheral portion of its impeller being substantially wider than the first stage channel and impeller thereby providing improved capacity and/or pressure characteristics when pumping liquefied gas.
